[57] CLAIM

The ornamental design for a clock or like article, as shown and described.

DESCRIPTION

FIG. 1 is a front elevational view of a clock showing my new design;

FIG. 2 is a front elevational view of another embodiment of my new design of FIG. 1;

FIG. 3 is a right side elevational view of the clock of FIG. 1 or FIG. 2;

FIG. 4 is a top plan view of the clock of FIG. 1 or FIG. 2;

FIG. 5 is a bottom plan view of the clock of FIG. 1 or FIG. 2;

FIG. 6 is a left side elevational view of the clock of FIG. 1 or FIG. 2;

FIG. 7 is a rear elevational view of the clock of FIGS. 3-6;

FIG. 8 is an alternative right side elevational view of the clock of FIG. 1 or FIG. 2;

FIG. 9 is an alternative top plan view of the clock of FIG. 1 or FIG. 2;

FIG. 10 is an alternative bottom plan view of the clock of FIG. 1 or FIG. 2;

FIG. 11 is an alternative left side elevational view of the clock of FIG. 1 or FIG. 2; and

FIG. 12 is a rear elevational view of the clock of FIGS. 8-11.
